UNITED STATES PATENT OFFICE.

JULES M. NESS, OF VERMILION, SOUTH DAKOTA.

DOUBLE ENVELOPE.

1,419,888.

Specification of Letters Patent. Patented June 13, 1922.

Application filed February 18, 1921. Serial No. 445,956.

To all whom it may concern:

Be it known that I, JULES M. NESS, a citizen of the United States, residing at Vermilion, in the county of Clay and State of South Dakota, have invented certain new and useful Improvements in a Double Envelope; and I do hereby declare the following to be a full, clear, and exact description of the invention, such as will enable others skilled in the art to which it appertains to make and use the same.

The object of the invention is to provide a double or plural pocket envelope having pockets of coextensive area and either or both of which may be sealed or closed, and which can be used successively for a message and the answer thereto, the fold forming the outside of the pocket or compartment which is sealed and used for the outgoing message being adapted to be torn off and the remainder of the package consisting of the other pocket or receptacle used for the return message and which in turn may be sealed to protect the message; and more particularly the object is to provide a package of this type which can readily and economically be constructed from a substantially rectangular blank of paper to avoid waste in cutting; and with these objects in view, the invention consists in a construction, combination, and relation of parts of which a preferred embodiment is shown in the drawing, wherein:

Figure 1 is a front view of an envelope embodying the invention.

Figure 2 is a plan view of the blank from which the envelope is formed.

Figures 3 and 4 are sectional views showing the blank loosely folded in opposite directions and indicating optional ways in which the receptacle can be formed from the same blank.

Figures 5 and 6 are transverse sectional views of the completed envelope folded as indicated respectively in Figures 3 and 4.

Figure 7 is an enlarged sectional view of the top of the envelope showing one compartment sealed and the other unsealed for succeeding use in connection with a return message.

Figure 8 is a similar view of the upper end of the envelope showing the previously sealed compartment removed and the previously unsealed compartment sealed to contain and protect the return message.

Figures 9 and 10 are enlarged detail sec-

tional views of the lower end of the envelope folded respectively as shown in Figures 3 and 4.

The envelope is formed from a blank as shown in Figure 2 consisting of an intermediate fold 20 and terminal folds 21 and 22 which are of corresponding area or are co-extensive when folded into superposed relation, and the terminal folds are provided at their outer edges with side sealing flaps 21^a and 22^a. The terminal folds, in the finished envelope, are arranged upon opposite sides of the intermediate fold, as indicated in Figure 3, and are gummed on their opposite surfaces as indicated by the shading. When the terminal folds are arranged upon the same side of the intermediate fold 20, as shown in Figure 4, they are gummed on the same side, and when folded each side sealing flap is folded in between the fold by which it is carried and of which it forms a part and the adjacent fold. It is adhesively secured to the latter so as to leave the full width of the fold to form the compartment or pocket of the envelope as will be seen by reference to Figures 3 and 4 and 5 and 6.

The intermediate fold is provided at opposite ends with closing flaps 24 and 23 which respectively constitute a covering or sealing flap and a bottom closing flap, while the terminal folds are provided at opposite ends with closing flaps 26 and 25, the former of which constitutes a covering or sealing flap, while the latter constitutes a bottom flap to close the lower end of one of the compartments or pockets of the finished envelope. The ends of the terminal folds opposite to the flaps carried thereby as above indicated may be cut away as indicated respectively at 26^a and 25^a mainly to lighten the weight or avoid bulkiness at the ends of the finished envelope and at the same time give ready access to the contents of the pocket, it being understood that as the blank is symmetrical so far as the construction at the ends of the folds are concerned, either end may be closed in the first instance to form the bottom of the envelope and leave the flaps at the opposite end to constitute the pocket or compartment closing means.

In other words not only can a blank constructed as described be folded in a plurality of ways as indicated in Figures 3 and 4 to form the separate pockets or compartments, the separating wall between the com-

- 2 compartments consisting of the fold 20 or one of the terminal folds as may be preferred, but either of the end flaps disposed at the extremities of the folds may be turned in 5 and sealed to close the bottoms of the pockets or compartments of the finished envelope, leaving the flaps at the opposite end thereof to be used as the sealing flaps, either of which may be sealed when a message 10 is sent out to permit of the use of the other sealing flap when the return message is placed in the remaining pocket or compartment of the envelope.
- Also as hereinbefore indicated after the 15 device has been used for an outgoing message, one of the pockets having its sealing flap secured to protect the message, the outer wall of such primarily used pocket or compartment may be torn off to permit of the 20 use of the other pocket or compartment for the return message, such further or second compartment or pocket having its own sealing flap by which the message placed therein may be protected.
- Having thus described the invention, what 25 I claim is:
1. A double pocket envelope consisting of a blank having an intermediate and terminal coextensive folds and gummed fastening flaps at the remote edges of the terminal 30 folds, the intermediate fold being provided at opposite ends with closing flaps and each of the terminal folds being provided at one end with a closing flap.
  2. A double pocket envelope consisting of a blank having an intermediate and terminal coextensive folds and gummed fastening flaps at the remote edges of the terminal 35 folds, the intermediate fold having terminal corresponding sealing and bottom flaps and the terminal folds respectively having a sealing and a bottom flap.
  3. A double pocket envelope consisting of a blank having an intermediate and terminal coextensive folds and gummed fastening 40 flaps at the remote edges of the terminal folds, the intermediate fold having terminal corresponding sealing and bottom flaps and the terminal folds respectively having a sealing and a bottom flap, arranged respectively at opposite ends thereof.
- In testimony whereof I affix my signature in presence of two witnesses.

JULES M. NESS.
